HUMIDIFIER APPARATUS

Milton A. Powers, Laguna Beach, Calif., assignor to Skuttle Manufacturing Company, Detroit, Mich., a corporation of Michigan

Application February 2, 1953, Serial No. 334,469

2 Claims. (Cl. 126—113)

The present invention relates to an apparatus for humidifying air in a warm air furnace system. More particularly, the invention relates to an arrangement for increasing the rate of humidification of air without enlarging the capacity of the humidifying apparatus.

In order to better understand the present invention it is believed it will be helpful if a brief description of the history of the development of humidifier equipment is given.

The first humidifiers used many years ago in hot air furnaces consisted of cast iron pans located usually under the firing door of the furnace but within the heated air space connected to the rooms to be heated. This pan was filled manually and evaporated water slowly. Usually it was dry due to lack of attention. Then came the automatic float control chamber which was sold as an accessory and usually installed by the customer or heating man. It was merely an automatic water level maintaining device which was connected to the city water supply and kept the old fashioned pan filled with water, thereby making it much more effective.

Realizing the very limited water evaporating capacity of any device located at a low level in the furnace, the next step was to place the humidifying device up high in the plenum chamber, usually just over the top of the furnace combustion chamber. Here there was plenty of heat, water evaporated rapidly, and in many cases during cold weather when the furnace was highly heated, water actually boiled from the humidifier. Under these circumstances there was no trouble in getting enough evaporation, in fact, in some cases trouble occurred due to excessive vapor in the air stream. All furnaces at this period were of gravity type, that is, air flowed to the rooms by convection due to the decreased weight of the hot air. Air flow areas in the furnace were relatively large, and the comparatively large bulk of the humidifier in the plenum chamber did not appreciably reduce the flow of air through the system.

Next came the incorporation of a forced air blower to the hot air furnace, the system now became dignified to the extent of being called a warm air furnace instead of a hot air furnace, and later this was further extended until now we call it a warm air heating and air conditioning system, and as such it is quite effective and satisfactory in millions of American homes. Oil and gas came to supply most of the heat, the systems became increasingly popular in smaller homes, and small automatic warm air systems now form the bulk of the home heating market. These various factors working together combined to set up heating plant requirements of such nature as to greatly restrict the designer of such equipment and this is the force which has led to the present invention, as will be seen.

When power driven blowers were attached to furnaces to circulate heat, several conditions arose in affecting the application of a humidifier. First, the furnace, in truth, became a warm air furnace, rather than a hot air furnace, due to the fact that the blower sent very large volumes of air over the furnace, and that air usually never became

2

very warm and seldom hot even in severely cold weather. Consequently, evaporation from the humidifier was reduced, as evaporation requires 970 B. t. u. or more for each pound of water evaporated. Making the humidifier pan larger to get more capacity was impractical as it further impeded the flow of air through the now even smaller plenum chamber around the furnace combustion chamber. This resulted in the widespread use of small evaporating pans in the humidifier, plus the use of Vapoglas evaporating plates which tremendously increase the evaporating capacity of a relatively small humidifier unit, such for example as the unit shown in the patent to Bottum, No. 2,569,512.

Generally speaking such a humidifier uses a pan of minimum cross section to impede the air flow to the least degree. The cross placed Vapoglas plates extend beyond the edges of the pan, but do not materially restrict the air flow, while at the same time serving most effectively to evaporate water into the passing airstream. Such is the status of the art insofar as humidification is concerned in the forced air furnace systems of today, but the trends toward even smaller and more compact heating units persist.

Thus, even though the humidifier apparatus of the type shown in the aforesaid Patent No. 2,569,512 is extremely efficient in its operation, there is still a pressing need for improvements over the prior art which will permit use of a small humidifier unit to fulfill the vapor needs in a small or large home, depending on how many Vapoglas plates are installed.

It is an object of the present invention to provide improved apparatus for use in humidifying air passing through a warm air furnace system, which apparatus is constructed and arranged so that the path of flow of dry warm air is directed across the evaporator elements to obtain the optimum rate of humidification of such air, thereby permitting the use of smaller humidifier equipment than was possible with the prior art devices.

It is still another object of the present invention to provide in a warm air furnace system an improved humidifier apparatus of the foregoing character which system is constructed and arranged so that the blower thereof discharges its dry air onto the evaporator elements of the humidifier unit so that optimum evaporation is obtained.

Other objects of this invention will appear in the following description and appended claims, reference being had to the accompanying drawings forming a part of this specification wherein like reference characters designate corresponding parts in the several views.

In the drawings:

Fig. 1 is a vertical sectional view showing one embodiment of the present invention wherein the humidifier unit is mounted in the plenum chamber of the furnace in such manner that warm air is directed between the evaporator elements of the unit; and

Fig. 2 is an enlarged side view of the humidifier unit. Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

One embodiment of the present invention is shown by way of example in Fig. 1, wherein a conventional humidifier unit, such as is shown in greater detail in Fig. 2, is employed. This humidifier unit includes a float tank 10 which is connected to an evaporator pan 12 by the water conduit 14. Water is supplied to the float tank 10 through the water inlet conduit 16, and the rate of flow

of this water is regulated by any conventional water level regulating means which will maintain the water level 18 within the evaporator pan 12 essentially constant regardless of varying rates of evaporation. Since the water level regulating means forms no part of the present invention it will not be shown nor described, but reference is made to the aforesaid patent to Bottum, No. 2,569,512 for a disclosure of one type of water level regulating means that may be used with the present invention.

Mounted within the evaporator pan 12 are a plurality of evaporating plates 20, which, as previously explained, tremendously increase the evaporating capacity of the humidifier unit. A more complete description of these evaporating plates 20 can be found in my prior patent, No. 2,271,829, granted February 3, 1942.

An arrangement which embodies the principles of the present invention can be seen in Fig. 1. Here the evaporating pan 20 and the evaporating plates 12 are mounted within the plenum chamber 30a which is disposed below the heat exchanger 24a. Air to be warmed is supplied by the blower 40 which has its discharge outlet extending through the top of the furnace wall 26a so that air can be directed onto and around the sides of the heat exchanger 24a to the plenum chamber 30a below. The air entering the plenum chamber 30a will flow over and between the evaporating plates 20. This humidified air will then be discharged through the duct 32a.

If desired, still other embodiments of the present invention may be employed. For example, the humidifier unit can be above the heat exchanger illustrated in Fig. 1, where the air will pass over the unit before entering the heating zone. From a practical point of view this upper location is often best because it can be more easily inspected and serviced than below the furnace.

From the foregoing descriptions of different embodiments of the present invention, it can be seen that one of the important features of the present invention is that the air which flows through the furnace is directed so that it flows downwardly toward the water in the evaporator pan 12 and between the evaporating plates 20. The improved operation of the humidifier unit which results from this change and reorientation of parts is very startling and unexpected.

As explained earlier, in very small furnaces with relatively high air flow velocities, any unit such as a humidifier, while small does tend to restrict the air flow past it. The standard evaporator pan which is conventionally used is three inches wide and about twelve inches long, the smallest possible for a reliable unit of sufficient evaporating capacity to fulfill the vapor needs in a small or large house, depending on how many evaporating plates are installed. A careful study of the air flow as it passes from below upward around the pan proper and between the evaporating plates of the prior conventional structures, shows that the airstream is diverted sideways by the interference of the pan, and consequently, it is now discovered that the humidifier unit is not as effective as it might be if the air stream could pass over the evaporating plates unimpeded by the bulk of the pan.

In working toward a solution of the problem of eliminating the pan as an obstruction to air flow, the principles of aerodynamics were applied and the airflow was reversed from the conventional bottom-to-top flow to a top-to-bottom flow. This had the effect of eliminating the relatively stagnant air pocket which was discovered to exist above the evaporator pan and between the evaporating plates when the conventional bottom-to-top flow was used. The evaporation was then materially increased because more relatively dry air had an opportunity to flow between the plates and scrub the same.

Actual airflow tests with a standard humidifier unit of the type shown in the aforesaid patent to Bottum, No. 2,569,512, equipped with 10 evaporating plates were made using the conventional bottom-to-top flow and the top-to-bottom flow. The results obtained from these tests clearly demonstrated the superiority of the present invention over the prior art arrangements. In conducting these tests the air temperature and humidity were substantially the same, and the rate of air flow and the duration of the tests were the same. During two hour tests the total evaporation when using the conventional bottom-to-top flow was 7.5 oz. of water; whereas, when using the top-to-bottom flow of the present invention, 11.4 oz. of water was evaporated. Thus, an increase of 52% in effectiveness was obtained when using the teachings of the present invention, and as a result it is now possible to reduce the present humidifier units by one-third in size and maintain present capacity. This means still further reduction of the unit as an obstruction in the airstream.

Having thus described my invention, I claim:

1. In combination with a furnace having a heat exchanger therein and having a plenum chamber below the heat exchanger and means forming an air passage through which air can be passed from above the furnace downwardly around and in heat exchange with the heat exchanger and thence downwardly to the plenum chamber, said plenum chamber having an outlet from said furnace, an open pan type humidifier unit mounted in said plenum chamber in the normal path of downwardly directed heated air and having its open portion facing upstream of said path, the pan of said humidifier unit supporting a plurality of evaporating plates in an upright position, said plates having their lower ends adjacent the bottom of the pan so as to be immersed in water carried by the pan, the upper portions of the plates extending beyond the confines of the pan into the normally heated airstream path for transferring moisture to the air, said plates being formed from a relatively rigid porous material to effect capillary action.
2. In combination with a furnace having a heat exchanger therein and having a plenum chamber below the heat exchanger and means forming an air passage through which a stream of air can be passed from above the furnace downwardly past and in heat exchange with the heat exchanger and thence downwardly to the plenum chamber, said plenum chamber having an outlet from said furnace, an open pan type humidifier unit having an open pan adapted to carry water at a preselected level, a plurality of thin T-shaped evaporating plates supported in said pan in an upright position with their lower ends below the water level of said pan and the upper portions extending beyond the confines of said pan, said pan being mounted within said plenum chamber in the normal path of downwardly directed heated air and having its open portion facing upstream of said path so that the flowing air will pass between the upper portions of said evaporating plates, the latter being formed from relatively rigid material which is porous so as to effect capillary action for transferring water from said pan to the air flowing between the plates, and a blower for blowing air past said heat exchanger and between said plates.
